UNITED STATES PATENT OFFICE.

GEORGE E. LAWRENCE, OF CRESTON, IOWA, ASSIGNOR OF ONE-HALF TO
JOSEPH J. MUMFORD, OF SAME PLACE.

BUCKLE.

SPECIFICATION forming part of Letters Patent No. 606,629, dated June 28, 1898.

Application filed March 13, 1897. Serial No. 627,345. (No model.)

To all whom it may concern:

Be it known that I, GEORGE E. LAWRENCE, a citizen of the United States, residing at Creston, in the county of Union and State of Iowa, have invented certain new and useful Improvements in Buckles; and I do hereby declare the following to be a full, clear, and exact description of the invention, such as will enable others skilled in the art to which it appertains to make and use the same.

My invention has relation to buckles for harness and for all the various purposes for which the buckle may be desired; and it consists, essentially, in providing two members movably secured together with respect to each other, one of said members being permanently secured in position near the end of a strap or other desired location.

The object of my invention is to provide a reliable securing device of the character specified which may be readily applied to its intended use and cheaply manufactured.

In the accompanying drawings, Figure 1 is a perspective view of my improved buckle, showing the "open" position. Fig. 2 is a longitudinal central section of the buckle, showing the closed position. Fig. 3 is a perspective detail of the fixed member. Fig. 4 is a perspective detail of the movable member. Fig. 5 is a transverse section of Fig. 2 on line *x x*.

Reference will be had to the various details of my invention by figures, the same figure referring to the same part throughout the several views.

In materializing my improved buckle I provide the base 1, having centrally-disposed slotted opening 2. Integrally formed with or otherwise secured to the base is the flange or side wall 3 and the section or cover 4, lying parallel with the base, preferably having the raised, centrally-disposed, longitudinal rib 5, the purpose of which will be hereinafter set forth. Movably secured to the base 1 is the locking-plate 6, having the outwardly-extending flange 7, designed to inclose the opening between the free edge of the cover or plate 4 and the base 1. Said holder 6 is mounted in position upon the base by means of the post 8, which is permanently fixed to the sliding member 6 and takes entirely through the

slotted aperture 2 when the end or head 9 thereof is upset or broadened to prevent the movable member from becoming disconnected from the base. The locking-plate 6 is separated and easily removed from the casing, when it and the tug can readily be put in working condition and then inserted in the casing. The stud 8 on this plate is some distance from the lower edge of the plate, and when inserted in the aperture of the tug the tug and plate can then be placed in the casing. This is readily and easily done, as the casing has an open side, and when the stud 8 is just above the upper edge of the casing the tug 65 and plate can be pushed in sidewise, or the tug can be inserted in the casing through its open side before being connected with the locking-plate. It is easier to place the tug in the casing through the open side than through 70 the bottom. The flange on plate 6 covers the open side, thereby fully protecting the parts therein. The post 8 extends outwardly sufficiently to provide a reliable means for anchoring the end of a strap or other object 75 which it is desired to secure, the free end of the post after passing through a suitably-provided aperture in said strap being received and guided by the groove 5, formed upon the cover 4. By this construction it will be observed that the plate 6, with its accompanying parts, may be reciprocated upon the base 80 1, either for the purpose of removing the end of a strap or for reliably securing it in position.

The operation or use of my improved buckle or securing device may be stated to be as follows: The fixed member or base 1 is anchored or secured in position upon the strap or other object by means of the rivets 10 or by other 90 preferred means. The movable member is then moved to the open position, when the end of the strap or other object having suitably-provided apertures is entered under the free end of the cover 4 and extended out 95 through the other end thereof into engagement with the post 8, which latter takes into the desired aperture, when by withdrawing said strap the movable member will be drawn entirely under the cover 4, the free end of 100 the post extending into the grooved seat 5, thus securing or locking the strap or other

object in position. The securing device may be unlocked by pulling upon the free end of the strap, thus causing the movable member to move from under the cover 4, when the strap may be disengaged from the post 8 and readjusted by entering the post into another aperture or it may be entirely withdrawn.

It will be seen that I have produced a reliably efficient securing device or buckle which may be cheaply manufactured and readily applied to use upon harness, suspenders, and all the various purposes for which a buckle is desirable, and having thus fully described the operation and construction thereof further reference is deemed unnecessary.

What I claim as new, and desire to secure by Letters Patent, is—

1. A buckle composed of a fixed casing having an open side and a vertical slot in its rear part and a groove in its front part, a movable plate having a flange to cover said open side and a fastening-stud working in said groove, as set forth.

2. A buckle consisting of a fixed casing, having an open side and a central vertical slot in its rear part, and an adjustable and removable plate having a flange to cover said open side, and a retaining-stud working in said vertical slot, as set forth.

3. A buckle composed of a fixed casing having a vertical groove in part of its front and a slot in its rear part, a movable plate having a fastening-pin working in said groove and slot, as set forth.

4. A buckle composed of a fixed casing having a vertical groove in its front and a slot in its rear part respectively and a movable plate having a fastening device working in said groove and slot, as set forth.

In testimony whereof I affix my signature in presence of two witnesses.

GEORGE E. LAWRENCE.
